CLAIM

The ornamental design for a wooden horse racing unit, as shown and described.

DESCRIPTION

FIG. 1 is a perspective front view of a wooden horse racing unit;

FIG. 2 is a front elevation view of the wooden horse racing unit;

FIG. 3 is a rear elevation view of the wooden horse racing unit;

FIG. 4 is a left side elevation view of the wooden horse racing unit; the right side view being a mirror image thereof;

FIG. 5 is a top plan view of the wooden horse racing unit; and,

FIG. 6 is a bottom plan view of the wooden horse racing unit.
